UNITED STATES PATENT OFFICE.

GEORGE W. FISHER, OF ST. LOUIS, MISSOURI.

CANE-MILL.

SPECIFICATION forming part of Letters Patent No. 638,629, dated December 5, 1899.

Application filed September 7, 1898. Serial No. 690,412. (No model.)

To all whom it may concern:

Be it known that I, GEORGE W. FISHER, a citizen of the United States, residing at the city of St. Louis, in the State of Missouri, have invented a certain new and useful Improvement in Cane-Mills, of which the following is a full, clear, and exact description, reference being had to the accompanying drawings, forming part of this specification.

The object of my invention is to provide a roller cane-mill with a perfect-working turn-bar, onto which is fastened the trash knife or scraper that cleans the front roller and over which the trash or bagasse is transferred from the pressure-point between the front and top rollers to the pressure-point between the top and back rollers, it being necessary in a properly-working trash knife or scraper that the front or scraping edge shall be firmly held against the front roller to prevent any fine bagasse from forcing its way between the roller and the edge of the scraper, thereby keeping the front roller clean and transferring the whole product to the pressure-point between the top and back rollers. To accomplish this desired action, the seats or bearings in the housing of the mill and in which the turn-bar rests must be a true plane, so that in gradually forcing the turn-bar forward to maintain the contact between the scraper and the front roller and from time to time to take up the wear on the edge of the scraper the arc of perfect contact of the scraper with the periphery of the roller shall always remain the same, which would not be the case if the front edge of the scraper were raised or depressed from its original setting. To accomplish this, I provide in the housings of a three-roller mill the usual windows with rest-blocks located therein and secured to the housing by bolts or otherwise, the upper surfaces of these rest-blocks being dressed to a true plane with each other. Into the upper part of the windows I fit and secure upper guide-blocks, the under or lower faces of which are dressed to a true plane parallel with the upper surfaces of the rest-blocks below, so that the two ends of the turn-bar when properly planed and fitted in the space between the rest-blocks and the upper guide-blocks may be moved at right angles with the axis of the front roller, as it were, between permanent guides. As a means for moving

the turn-bar I provide a lever at each side of the mill, these levers being journaled to the upper guide-blocks and being perforated to receive projections on the ends of the turn-bar, so that by moving the free ends of the levers the turn-bar may be adjusted toward the front roller as its edge becomes worn, and thus a close fit be constantly maintained between the scraper and periphery of the front roller.

My invention consists in features of novelty hereinafter fully described, and pointed out in the claims.

Figure I is a side view of a cane-mill provided with my improvement, the journals of the rollers being shown in section. Fig. II is a vertical transverse section taken on line II II, Fig. III, the rollers being shown in end view with the journals in section. Fig. III is a vertical longitudinal section of the machine, the turn-bar and rollers being shown in elevation. Fig. IV is an enlarged detail perspective view showing one end of the turn-bar and scraper, part of the housing of the mill, the rest-blocks, and the upper guide-blocks. Fig. V is a detail vertical section. Fig. VI is a view corresponding to Fig. I, but illustrating a modified means for adjusting the turn-bar. Fig. VII is a like view, but showing another modified means for adjusting the turn-bar. Fig. VIII is a detail perspective view of the modification shown in Fig. VII.

Referring to the drawings, 1 represents the housing of the mill; 2, the front roller; 3, the top roller, and 4 the back roller. These parts are of the ordinary form of construction and require no explanation.

To provide an effective, durable, and perfect working device for transferring the bagasse from the front roller to the back roller is, as stated, the object of my invention.

5 represents a "turn-bar," so called for the reason that it, with the scraper, turns the direction of the bagasse from the peripheral face of the front roller. This bar is provided with ends 6, having flat upper and lower faces and extending into windows or openings 7 in the housing of the machine.

8 represents a scraper bolted or otherwise secured to the upper face of the turn-bar and the front edge of which is adapted to bear against the peripheral surface of the front

roller and remove the bagasse therefrom, which passes over the scraper, entering between the upper and back rollers.

9 represents rest-blocks located in the windows 7 beneath the ends 6 of the turn-bar, as clearly shown in Fig. IV, and 10 represents upper guide-blocks located in the windows 7 above the ends 6 of the turn-bar. The upper faces of the rest-blocks and the lower faces of 10 the upper guide-blocks, together with the upper and lower faces of the ends of the turn-bar, are planed off smooth on parallel lines, so as to produce a perfect fit and insure the movement of the turn-bar on a line at right angles 15 to the axis of the front roller. I prefer to bolt the rest-blocks to the housing, as shown at 11, Fig. V, and the upper guide-blocks are provided with ears 12, secured to the housing by means of bolts 13 fitting in vertical slots 20 14, formed in the ears 12, so that the upper guide-blocks may be adjusted in a vertical direction when necessary to insure a close fit upon the ends of the turn-bar. If desired, the parts may be so proportioned as to permit 25 the insertion of a number of thin plates 15 between the ends of the turn-bar and the rest-blocks, as shown in Fig. V, and should it be desired to lower the turn-bar slightly one or more of these plates may be removed 30 from between the ends of the turn-bar and the rest-blocks and be placed between the upper guide-blocks and the housing.

The outer faces of the upper guide-blocks are provided with journals 16 to receive the 35 upper ends of levers 17, the levers having elongated perforations 18 to receive projections 19 on the ends of the turn-bar. The lower ends of the levers are provided with threaded rods 20, received by ears 21 on the housing of 40 the machine. The rods are provided with nuts 22, and by adjusting these nuts the free ends of the levers may be moved to keep the front edge of the scraper constantly against the periphery of the front roller.

45 Instead of employing the levers for shifting the turn-bar and scraper threaded rods 23 may be employed, as shown in Fig. VI, the ends of the turn-bar being extended, as shown in Fig. VIII, to receive the rods. The ends 50 of the rods are threaded to receive nuts 25 on either side of ears 24 on the housing through which the rods pass. Instead of having a pair of rods extending to opposite sides of the machine, as shown in Fig. VI, a single rod at 55 each end of the turn-bar may be employed, as shown at 26, Fig. VII, and as shown also in Fig. VIII, these rods extending in the direction of the front roller and being threaded to receive nuts 27 on either side of ears 28, formed 60 on the journal-boxes of the front roller.

By providing the upper guide-blocks with 65 fulcrums renewable journals are furnished for the levers, and these journals are brought very close to the projections on the ends of the turn-bar, so that the purchase obtained for the levers 17 is very great, and the turn-bar can thus be moved with ease when it be-

comes necessary to adjust it; and by providing the upper guide-blocks provision is afforded for a vertical adjustment of the turn-bar without changing the relative distance between the pivotal or fulcrum points of the levers and their points of connection with the turn-bar, and by providing these blocks above the ends of the turn-bar provision is also made 70 for renewable upper bearings for the ends of the turn-bar and bearings which can readily be planed off, so as to provide smooth parallel faces for contact with the upper faces of the ends of the turn-bar. By providing the rest-blocks provision is made for renewable bearings beneath the ends of the turn-bar, which can readily be planed off to provide smooth contact-faces for the ends of the turn-bar, and at the same time windows or openings of 75 sufficient size may be made in the housing to permit of the withdrawal of the larger central part of the turn-bar when necessary for the purpose of repair or for renewal.

I claim as my invention—

1. A cane-mill comprising a housing having windows or openings formed in the sides thereof, rest-blocks having smooth faces and located in the windows or openings, a turn-bar having its ends formed with flat upper and lower faces and supported in the windows or openings on the rest-blocks, the guide-blocks having smooth faces and located in the windows or openings and surmounting the ends of the turn-bar, and means whereby the ends of the turn-bar are moved laterally between the rest-blocks and the guide-blocks, for adjusting the turn-bar; substantially as described.

2. A cane-mill comprising a housing having windows or openings formed in the sides thereof, rest-blocks having smooth faces and located in the windows or openings, a turn-bar having its ends formed with flat upper and lower faces and supported in the windows or openings on the rest-blocks, the vertically-adjustable guide-blocks having smooth faces and located in the windows or openings, and surmounting the ends of the turn-bar, and means whereby the ends of the turn-bar are 100 moved laterally between the rest-blocks and the vertically-adjustable guide-blocks for adjusting the turn-bar; substantially as described.

3. A cane-mill comprising a housing having windows or openings formed in the sides thereof, rest-blocks having smooth faces and located in the windows or openings, a turn-bar having its ends formed with flat upper and lower faces and supported in the windows or openings on the rest-blocks, the guide-blocks having smooth faces and located in the windows or openings and surmounting the ends of the turn-bar, means whereby the ends of the turn-bar are moved laterally between the rest-blocks and the guide-blocks located above the ends of the turn-bar, for adjusting the turn-bar, and means for raising and lowering the turn-bar; substantially as described.

4. A cane-mill comprising a housing having windows or openings formed in the sides thereof, rest-blocks located in the windows or openings, a turn-bar having its ends formed with flat upper and lower faces, provided with end projections and supported in the windows or openings on the rest-blocks, the guide-blocks located in the windows or openings and surmounting the ends of the turn-bar, levers pivoted to the guide-blocks and engaging with the projections on the ends of the turn-bar, whereby the ends of the turn-bar are moved laterally between the rest-blocks and the guide-blocks for adjusting the turn-bar, and means for adjusting the levers; substantially as described.

5. A cane-mill comprising a housing having

windows or openings formed in the sides thereof, rest-blocks having smooth faces and located in the windows or openings, a turn-bar having its ends formed with flat upper and lower faces and supported in the windows or openings on the rest-blocks, the guide-blocks having smooth faces and located in the windows or openings and surmounting the ends of the turn-bar, and levers pivoted to the housing at one end and at the other end provided with means for adjusting the turn-bar, whereby the latter is held and moved only in a horizontal direction; substantially as described.

GEO. W. FISHER.
